Primary Examiner — Marissa J Cash*Assistant Examiner* — Altaira J Swangin(74) *Attorney, Agent, or Firm* — Sughrue Mion, PLLC(57) **CLAIM**

The ornamental design for a hair roll, as shown and described.

DESCRIPTION

FIG. 1 is a top, front perspective view of the hair roll, showing the new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines in the drawing figures depict portions of the hair roll and form no part of the claimed design.

1 Claim, 6 Drawing Sheets(56)
